CLAIM

The ornamental design for a shoe outsole, as shown and described.

DESCRIPTION

FIG. 1 is a front perspective view of a shoe outsole showing my new design;

FIG. 2 is a bottom view thereof; and,

FIG. 3 is a rear perspective view thereof.

The solid lines are claimed and represent claimed boundaries of the design. The broken lines that are concentric to the solid lines represent unclaimed boundaries of the design. The broken lines showing the remainder of the shoe outsole are for environmental purposes only and form no part of the claimed design.
